UNITED STATES PATENT OFFICE

CLIFFORD L. SNYDER, OF DETROIT, MICHIGAN, ASSIGNOR TO EVANS PRODUCTS COMPANY, OF DETROIT, MICHIGAN, A CORPORATION OF DELAWARE

CHOCK BLOCK

Application filed August 10, 1931. Serial No. 556,214.

This invention relates to certain new and useful improvements in chock blocks.

The primary object of the invention, is to provide a chock block for the support of a motor vehicle wheel, wherein standardized lumber such as, 2 x 2, 2 x 4, 2 x 6 or the like, may be employed in the manufacture of the chock block so that relatively short pieces or low priced lumber may be utilized in the manufacture of the block, and waste eliminated.

A further object of the invention, is to construct a chock block from lumber of standard sizes as before mentioned with the lumber cut or split at certain angles and assembled in a manner to provide a dished or substantially concave tread surface and possessing the strength of the usual solid chock block constructed of a single piece of material.

With the above and other objects in view that will become apparent as the nature of the invention is better understood, the same consists in the novel form, combination and arrangement of parts hereinafter more fully described, shown in the accompanying drawings and claimed.

In the accompanying drawings:—

Figure 1 is a side elevational view of a chock block constructed in accordance with the present invention,

Figure 2 is a top plan view of the chock block showing the side walls, the intermediate spacer bar, and the brace heel,

Figure 3 is a cross sectional view taken on lines 3—3 of Figure 1 showing the side walls secured to the spacer bar,

Figure 4 is a cross sectional view taken on lines 4—4 of Figure 1 showing the projection at the upper end of the brace heel extending between the side walls of the block,

Figure 5 is a fragmentary prospective view of a 2 x 4 timber diagonally cut lengthwise thereof and placed as to provide the side walls of the chock block,

Figure 6 is a fragmentary prospective view of a 2 x 4 timber with a transverse cut longitudinally to provide rectangular spacer bars,

Figure 7 is a side elevational view of a

chock block wherein the spacer bar comprises an uncut 2 x 4 timber,

Figure 8 is a cross-sectional view taken on lines 8—8 of Figure 7,

Figure 9 is a side elevational view of a chock block wherein the side walls are cut from a 2 x 6 timber with a split 2 x 6 spacer bar interposed therebetween,

Figure 10 is a cross-sectional view taken on lines 10—10 of Figure 9,

Figure 11 is a detailed sectional view of the tread portion of a chock block showing the tread surface of the spacer bar transversely grooved, and

Figure 12 is a side elevational view of the chock block wherein an angle corner edge of the brace heel constitutes the support.

In the form of the invention as shown in Figures 1 to 6, there is illustrated a chock block comprising side walls, an intermediate spacer bar and a brace heel, all of the parts being nailed or otherwise secured together. As shown in Figure 5, a 2 x 4 timber is diagonally cut between the side walls thereof and lengthwise upon the line 15 to provide side wall sections 16 and the 2 x 4 timber illustrated in Figure 6 is transversely cut between the side walls lengthwise thereof upon the line 17 to provide spacer bars 18.

The side walls 16 of the chock block are placed as illustrated in Figures 1 to 4 with the angle cut faces 15^a opposing each other and separated by the intermediate spacer bar 18, this arrangement providing a substantial cavity in the face of the chock block for the support of a vehicle wheel.

The spacer bar 18 projects rearwardly of the side walls 16 as at 18^a to add additional strength to the block, the upper end of the spacer bar 18 terminating at a point spaced from the upper ends of the side bars, while the lower end of the spacer bar and side bars terminate in the same place and are angularly cut as at 19 to provide an inclined bearing end for the chock block as illustrated in Figure 1. The

side walls 16 and spacer bar 18 are secured together by nails 20 or other fastening devices as illustrated in Figures 1 to 3.

The brace heel comprises a piece of 2 x 6 timber 21 to provide a substantially inverted

V shaped chock block, the upper corner edges of the brace heel being cut away as at 22 to provide a center block projection 24 received between the upper ends of the side bars 16 to rest upon the upper end of the spacer bar 18 as shown in Figure 2, a nail or other fastening device 25 being provided for securing block projection 24 to the upper end of the spacer bar 18. The lower end of the brace heel 21 is angularly cut as at 26 for flat surface contact with a floor or other support. It will therefore be observed that a chock block of substantial construction embodying an abundance of strength, may be constructed from practically waste lumber and a material saving effected, the block in all appearances being substantially the same as the usual one piece block with a facial cavity for the support of the vehicle wheel and side walls to prevent lateral displacement.

In the form of the invention illustrated in Figures 7 and 8, the side walls 16^a are angularly cut from a 2 x 4 timber and the spacer bar 18^a is an uncut 2 x 4 timber that projects considerable distance rearwardly of the side walls 16^a to provide an additional nailing support for the rear brace heel 21^a as illustrated in Figure 7.

The chock block shown in Figures 9 and 10 with side walls 16^b is cut from a 2 x 6 timber which provides side walls of greater depth and the spacer bar 18^b is an uncut 2 x 4 timber interposed between the side walls, but does not project rearwardly thereof as illustrated in Figure 10. The heel brace 21^b is formed of a 2 x 6 timber and has a connection between the upper ends of the heel braces 21^a and 21^b shown in Figures 7 to 10 is the same as illustrated in connection with

Figures 1 to 6.

In the form of the invention illustrated in Figure 11 side bars 16^c are separated by a spacer bar 18^c that has its face transversely concaved as at 18^c to provide the usual continuous transverse curve found in the tread surfaces of chock blocks.

In each form of the invention previously discussed, the lower end of the brace heel 21 is cut at an angle to provide a flat bearing surface, but if desired, and as illustrated in Figure 12, the lower end of the brace heel 21^d may have the usual straight angle end 21^d with a corner edge of the heel providing a support for the heel brace.

While there is herein shown and described the preferred embodiment of the invention, it is nevertheless to be understood that minor changes may be made therein without departing from the spirit and scope of the invention as claimed.

What I claim as new is:

1. In a chock block, a tread wall including side bars, a central spacer bar and an inclined heel brace.
2. In a chock block, a tread wall including

side bars, a central spacer bar and an inclined heel brace, and the opposed faces of the side bars outwardly of the spacer bar flaring outwardly.

3. In a chock block, a tread wall including 70 side bars, a central spacer bar and an inclined heel brace, the spacer bar terminating at its upper end below the upper ends of the side bars and a block projection on the heel brace extending between the upper ends of 75 the side bars.

4. In a chock block, a tread wall including 80 side bars, a central spacer bar and an inclined heel brace, and the opposed faces of the side bars outwardly of the spacer bar flaring outwardly, the spacer bar terminating at its upper end below the upper ends of the side bars and a block projection on the heel brace extending between the upper ends of 85 the side bars.

5. In a chock block, a tread wall including 90 side bars, a central spacer bar and an inclined heel brace, the spacer bar terminating at its upper end below the upper ends of the side bars and a block projection on the heel 95 brace extending between the upper ends of the side bars, and means for fastening the side bars to the spacer bar and the block projection to the spacer bar.

6. In a chock block, a tread wall including 100 side bars, a central spacer bar and an inclined heel brace, and the opposed faces of the side bars outwardly of the spacer bar flaring outwardly, the spacer bar terminating at its upper end below the upper ends of the side bars and a block projection on the heel brace 105 extending between the upper ends of the side bars, and means for fastening the side bars to the spacer bar and the block projection to the spacer bar.

7. In a chock block, a tread wall including 110 side bars, a central spacer bar and an inclined heel brace, the spacer bar terminating at its upper end below the upper ends of the side bars and a block projection on the heel brace 115 extending between the upper ends of the side bars, and said spacer bar projecting rearwardly of the side bars.

8. In a chock block, a tread wall including 120 side bars, a central spacer bar and an inclined heel brace, and the opposed faces of the side bars outwardly of the spacer bar flaring outwardly, the spacer bar terminating at its upper end below the upper ends of the side bars and a block projection on the heel brace 125 extending between the upper ends of the side bars, and said spacer bar projecting rearwardly of the side bars.

9. In a chock block, a tread wall including 130 side bars, a central spacer bar and an inclined heel brace, and the tread face of the spacer bar being transversely curved.

10. In a chock block, a tread wall including side bars, a central spacer bar and an inclined heel brace, and the opposed faces of the side 135

bars outwardly of the spacer bar flaring outwardly, and the tread face of the spacer bar being transversely curved.

11. The method of constructing a chock
5 block consisting of longitudinally splitting
at a transverse angle, a timber that is rec-
tangular in cross section, rearranging the
two pieces of split timber to present the angle
faces in opposed outwardly flaring relation,
10 positioning and securing a spacer bar be-
tween the two pieces of split timber and angu-
larly attaching a heel brace to the side bars
and spacer bar.

In testimony whereof I affix my signature.

15 CLIFFORD L. SNYDER.
